UNITED STATES PATENT OFFICE

1,926,497

SLUB-CATCHER AND YARN-CLEANER

Edward F. Parks, Providence, R. I., assignor to
Universal Winding Company, Boston, Mass., a
corporation of Massachusetts

Application October 22, 1930. Serial No. 490,492

14 Claims. (Cl. 28—68)

This invention relates to improvements in slub-catchers and yarn-cleaners for removing slubs, bunches, lint, motes, and other foreign matter from thread, yarn and like filaments during the process of winding or otherwise transferring the material in the textile art.

In the following specification and claims the term "yarn" is used in a generic sense to indicate any kind of filament or strand material.

One object of the invention is to provide a device of the type specified having a slit or opening through which the yarn draws with means for adjusting the width of the slit with great precision and accuracy in accordance with different sizes or thickness of the material to be operated upon.

Another object of the invention is to provide a device of the type specified wherein the yarn-slit or opening is maintained of uniform width throughout its entire length under all conditions of adjustment so that the device will operate with maximum efficiency whatever the position of the strand drawing through the slit.

Another object of the invention is to provide a device of the type specified wherein the opposite elements which form the slit are automatically self-aligning to maintain the width of the slit uniform after adjustment.

Another object of the invention is to provide a device of the type specified of simple construction, economical to manufacture, proof against derangement or getting out of order and generally more efficient for the purposes specified.

Further objects of the improvement are set forth in the following specification which describes a preferred form of construction of the invention, by way of example, as illustrated by the accompanying drawings. In the drawings:

Fig. 1 is a view of a conventional type of winding machine showing the present improved slub-catcher and yarn-cleaner applied to use therewith for cleaning the yarn as it delivers to the package being wound;

Fig. 2 is an enlarged plan view of the improved device;

Fig. 3 is a side view of the same;

Fig. 4 is an end view of the device showing how the yarn feeds therethrough;

Fig. 5 is a vertical sectional view taken on the line 5—5 of Fig. 2;

Fig. 6 is a perspective view of the resilient clamping-means for the adjustable element of the device;

Fig. 7 is a plan view showing a modified form of construction of the device; and

Fig. 8 is a further enlarged end view of this latter form of construction embodying the invention.

The present invention relates to improvements in that type of slub-catchers or yarn-cleaners constituted by two opposite members having portions arranged in parallel spaced relationship to form a slit or opening through which the yarn is drawn to scrape lint, motes and other foreign matter therefrom, while also providing for the detection of slubs and abnormal enlargements on the yarn to prevent their passage through the slit whereby the yarn is broken so that the imperfect section may be removed.

In the present embodiment of the invention the two opposite slit-forming members are constituted one as a fixed blade or plate having an edge across which the yarn draws, and the other as a cylindrical pin or rod which is adapted to be adjusted to bring its periphery into different positions with respect to the edge of the blade to vary the width of the slit therebetween in accordance with the size of the yarn to be operated upon. The adjustable member has a bearing in which it is rotatably mounted and its cylindrical yarn-engaging portion is disposed eccentrically with respect to the axis of rotation whereby to cause its periphery to approach or recede from the edge of the fixed blade to decrease or increase the width of the slit. The present improvement is concerned particularly with means for rotatably mounting the adjustable element or eccentric pin to cause it to be maintained with its side invariably in exact parallel alignment with respect to the edge of the blade with which it cooperates in whatever position of adjustment it may be set.

Referring to the drawings, in Fig. 1, 2 designates the frame of a well-known type of winding machine carrying a rotatable spindle 3 on which the cop or package C is wound, and embodying a traversing thread-guide 4 slidable in a traverse-frame 5 and reciprocated longitudinally of the winding-spindle to lay the yarn in crossing helices which build up the layers of the yarn mass. The yarn γ feeds through a tension-device, designated generally at 7, comprising opposite plates 8 having alternate bars across which the yarn draws to give an undulating course thereto whereby to apply resistance to its draft. The operation of the machine is controlled through suitable stopping-mechanism which causes the arrest of the winding when the yarn breaks or its supply is exhausted, a pivoted drop-wire 9 being provided to initiate the action of the stopping-mechanism. The drop-wire 9 is sus-

pended from a pivot 10 and provided at its lower end with a bar 12 under which the yarn y draws as it feeds to the thread-guide 4. Upon breakage or exhaustion of the yarn the drop-wire 9 swings under the action of gravity to engage its inner end with a rotating knock-off wheel 13 which thereupon functions to move the bar to release the detent-device and thereby render the stopping-mechanism active. These parts of the winding machine are all well known to those versed in the art and are referred to herein merely to denote the relation of the drop-wire to the slab-catcher and its method of cooperation therewith.

15 The present improved slab-catcher, indicated generally at 15 in Fig. 1, is shown as mounted on the top of the tension-bracket 16 which supports the tension-plates 8 so that the yarn drawing through the tension-device feeds directly through the slit in the slab-catcher and thence under the crossbar 12 of the drop-wire 9 to the package being wound. It is to be understood, however, that the present form of slab-catcher or yarn-cleaner may be used with different types of winding machines and also applied to other apparatus employed in the transfer of yarn in various processes of the textile art.

20 Referring to the detailed views, the present device comprises a base or mounting 20 constructed in the form of a flat plate having a trough-like channel or groove 21 extending laterally across its top. A screw 22 passes down through a hole in one side of the base or mounting 20 and is screwed into the top of the tension-bracket 16 or other support on which the device is mounted with a dowel-pin 23 for holding the mounting from turning on the screw. In the present illustration, the dowel-pin 23 is constituted as an upright wire rod on which the tension-plates 8 are hinged.

25 On the opposite side of the groove or channel 21 in the base 20 is a flat horizontal finished face 24 serving as a seat for one of the operative elements of the device, in this instance, the fixed plate or blade 25 across the edge of which the yarn draws. One side of the blade 25 has a straight edge 26 overhanging the side of the channel or groove 21 and projecting beyond the side of the base 20 with its outer end beveled off at 27 and then curved toward the rear, more or less in the shape of a knife-blade. The blade 25 is secured against its seat 24 on the base 20 by means of a pair of screws 28. The screws 28 are also employed to attach a relatively thin sheet-metal clamp-member or plate 30 to the top of the blade 25. The clamp-member 30, shown in perspective view in Fig. 6, provides a bearing for the other operative member of the slab-catcher constituted by the rotatable eccentric pin 35.

30 Referring particularly to Fig. 5 of the drawings, the clamp-member or plate 30 is clamped down against the top of the blade 25 and projects outwardly beyond its edge 26 to bridge the top of the channel or groove 21. The projecting portion of the clamp-member 30 is slotted at 31, see Fig. 6, to form three tines or fingers 32, 33 and 34 which are curved or of arcuate shape for a purpose as later explained. A fourth finger 36 is bent upwardly in inclined relation to the top of the clamp-member 30 to provide a rest or stop for the crossbar 12 of the drop-wire 9, its cooperative relation therewith being shown in Fig. 1 and illustrated diagrammatically in Fig. 4 of the drawings.

35 The adjustable member or eccentric pin 35

is constructed with a bearing portion 37 of slightly enlarged diameter formed eccentric with respect thereto, see Figs. 2 and 4. The enlarged bearing portion 37 of the pin 35 is disposed with its side engaging the edge of the blade 25 throughout that portion of its length which is supported on top of the base 20, with the eccentric portion of the pin extending outwardly in parallel spaced relation with respect to the working edge of the blade. The bearing portion 37 of the eccentric pin 35 seats upon a raised boss or ledge 40 in the bottom of the channel or groove 21 in the base 20, the surface of the boss being finished to provide a level rest to hold the pin in alignment with the edge of the blade 25.

40 The bearing portion 37 of the eccentric pin 35 is clamped in firm engagement with the edge of the blade 25 by means of the tines or spring-fingers 32, 33 and 34 on the holder or clamp-member 30. The two fingers 32 and 34 encompass a portion of the enlarged bearing end 37 of the pin, while the central finger 33 fits within a circumferential groove or recess 41 formed substantially mid-way of the portion 37 of the pin 35. Through this arrangement the finger 33 is adapted to hold the eccentric pin 35 from longitudinal movement by engagement with the ends of the groove or recess 41.

45 The outer end of the pin 35 is provided with a hexagonal socket 42 for receiving a wrench by means of which the pin is rotated in its bearing.

50 On one side of the channel or groove 21 in the base 20 is an upright finger 43 which serves as a stop to limit the swinging movement of the drop-wire 9 when the latter operates to set the stopping-mechanism in motion.

55 The parts of the device are assembled by attaching the blade 25 to the base 20 with the clamp-plate 30 held down against the top of the blade by means of the screws 28. The eccentric pin or adjustable element 35 of the device is placed in the channel or groove 21 in the top of the base 20 with its bearing portion 37 resting on top of the seat 40 and the spring-fingers 32, 33 and 34 of the clamp-member 30 engaged across the top thereof; the central finger 33 fitting into the peripheral groove 41 in the pin to lock it against longitudinal movement.

60 To adjust the width of the slit or opening between the side of the pin 35 and the edge of the fixed blade 25 a wrench of suitable type is inserted into the hexagonal socket 42 in the end of the pin to turn the latter in its bearing. It has been noted that the main portion of the pin 35 is formed eccentric with respect to the axis of its bearing portion 37 and, consequently, when the pin is rotated by means of the wrench the side of the pin adjacent the edge of the blade 25 will be adjusted toward and away therefrom. The pressure of the spring-fingers 32, 33 and 34 maintains the bearing portion 37 of the pin clamped firmly against the edge of the blade 25 to hold the side of the pin in alignment with the working edge of the blade and further provides a slight frictional resistance to the rotation of the pin so that it is prevented from unwarranted turning movement.

65 The yarn y is drawn up from its source of supply, usually arranged below, passed through the tension-device 7 as shown in Fig. 1 and led through the slit or opening between the side of the pin 35 and the edge of the blade 25. Thence the yarn draws under the crossbar 12 of the drop-wire 9 and leading up to the thread-guide 4 is traversed by the latter longitudinally of the winding-

spindle 3 to wind it thereon. During the passage of the yarn through the sub-catcher or cleaner the sides of the slit act to scrape lint, fluff, motes and other foreign matter from its surface and when a knot, bunch, slab or other enlargement on the yarn encounters the edge of the blade it is prevented from passing through the slit. The catching of the slab in this way causes the yarn to be broken, whereupon the drop-wire 9 is released and caused to cooperate with the rotating knock-off wheel 13 which releases the detents to initiate the operation of the stopping-mechanism. The operation of the winding machine is thereby arrested so that the operator may remove the imperfect portion of the yarn and piece up the end to again prepare the machine for winding.

In Figs. 7 and 8 of the drawings the invention is shown as embodied in a modified form of construction wherein a ratchet is provided for positively controlling the rotation of the adjustable element which cooperates with the edge of the fixed blade 25 to form the slit through which the yarn draws; provision for adjustment of the device in this case being made by constructing the ratchet teeth of different depths as will be later explained.

In this latter form of construction the cylindrical rod or pin 45 is of substantially the same form as that first described, but its bearing portion 46 is made concentric with the axis of the pin instead of being offset or eccentrically disposed with respect thereto. The bearing portion 46 of the pin 45 is provided at either end with a series of ratchet teeth 47, the outer periphery or points of which are formed concentric with the axis of the pin, while the inclined flat portions of the teeth are arranged eccentric with respect thereto. Referring to Fig. 8, it will be seen that the successive teeth are of varying depth, the deepest tooth being at 48 and the remaining teeth being of gradually less depth around to the tooth 49 which is of least depth.

As in the form of construction first described the adjustable member or pin 45 is arranged with its inner end resting on the seat or rest 40 in the center of the channel 21 in the base 20 and its toothed bearing portion 46 clamped against the edge of the fixed blade 25 with one of the teeth engaging the bottom edge of the blade. The clamp-blade 50 is of substantially the same form as illustrated in Fig. 6 except that its curved portion 51 is not divided into a plurality of fingers. Referring to Fig. 7 the curved extension 51 of the blade 50 overlies the top of the toothed bearing portion 46 of the pin 45 to engage against the peripheral edges of the teeth 47. At the outer end of the curved portion 51 of the clamp-member 50 is a relatively narrow centrally-disposed finger 52 which projects into a peripheral groove 53 formed in the bearing portion 46 of the pin. The finger 52 engages the sides of the groove 53 to prevent longitudinal movement of the pin 45 in its bearing.

In adjusting the pin 45 to vary the width of the slit between its periphery and the edge of the fixed blade 25 a wrench is inserted into the hexagonal socket 42 in the end of the pin to rotate the latter in a clockwise direction. As the pin is rotated in this manner the teeth 47 on its bearing portion 46 will engage successively with the lower edge of the blade 25, and since the flat portions of the teeth are eccentric with respect to the axis of the pin a relative lateral adjustment is effected between the pin and the blade 25.

When the pin 45 is turned to bring its deepest tooth 48 into engagement with the edge of the blade 25 the pressure of the spring extension 51 on the clamp-blade 50 will cause the pin to be adjusted into close association with the edge of the blade 25 to provide a minimum width of slit therebetween. Now, as the pin is rotated in a clockwise direction the successive teeth of lesser depth will come into engagement with the edge of the blade 25 to gradually force the pin 45 away from the blade. In Fig. 8 of the drawings the pin 45 is shown as adjusted with the tooth 49 of minimum depth engaged with the edge of the blade 25 and with this setting of the pin the slit between its side and the edge of the blade 25 will be opened to maximum width.

With the last described form of construction as the pin 45 is turned in a clockwise direction to adjust its side toward and away from the edge 26 of the fixed blade 25 rotation in the opposite direction is prevented by the engagement of the teeth with the blade; the pressure of the teeth against the edge of the blade 25 also causing frictional resistance to the turning of the pin during its adjustment. The method of operation of this latter form of construction is substantially the same as that of the embodiment first described, the yarn being drawn through the slit or opening between the side of the pin 45 and the edge of the fixed blade 25 to scrape its sides clean while preventing the passage of slubs, knots and enlargements through the device.

It will be observed from the foregoing that the present invention provides a particularly compact, simple and efficient sub-catcher or yarn-cleaner which may be manufactured at relatively low cost. The clamping arrangement for the adjustable element of the device insures that the side of the pin shall always be maintained in correct alignment with the edge of the scraper blade 25 without dependence upon screws, nuts or other forms of fastening means for holding it in place. It is only necessary that the periphery of the eccentric bearing portion of the pin be machined or ground true with its axis and that the straight edge of the blade 25 be made true to insure the proper cooperation between the parts. The improved construction of the mounting for the rotatable adjustable element permits the removal of this element for cleaning the parts when required, while also adapting it to be readily replaced when it becomes worn.

As another feature of improvement it will be noted that the device is practically proof against being tampered with, for even though the pin be pried away from the edge of the scraper blade 25 the resiliency of the spring-clamp will cause it to be automatically brought back into place with the slit maintained of uniform width throughout its length. Where the winding or other work performed on the machine is being done on a "piece work" basis it is sometimes the practice of operators to pry open the sub-catcher to allow the passage of slubs, knobs and bunches therethrough so as to have less stoppages in the winding or other operation. The present device is designed to prevent such unauthorized tampering with or maladjustment of the sub-catcher, the adjustment of the width of the slit being capable of accomplishment only through the use of a special wrench which is held by the foreman or other authorized person attending the machines.

While the present improved sub-catcher or yarn-cleaner is herein described and illustrated

as embodied in a preferred form of construction and shown with one modification of its arrangement, it is to be understood that further changes in the design and structure of its parts may be made without departing from the spirit or scope of the invention. Therefore, without limiting myself in this respect, I claim:

1. In a slub-catcher or yarn-cleaner, the combination of a stationary scraper-element adapted 10 to engage the yarn, a cylindrical pin arranged substantially parallel with respect to the stationary element to form a longitudinal slit therebetween through which the yarn draws, said pin having an enlarged eccentric bearing portion engaging 15 against the edge of the stationary element, and means for holding the bearing portion of the pin clamped against the edge of the first element to maintain said elements in uniform spaced relationship.
2. In a slub-catcher or yarn-cleaner, the combination of an element having an edge across which the yarn is adapted to draw, a second element having a bearing abutting the edge of the first element throughout a portion of its 25 length and a portion extending therebeyond with its side in parallel spaced relation with respect to said edge, and resilient clamping-means for maintaining the second element engaging against the edge of the first element.
3. In a device of the type specified, the combination of a fixed blade having an edge across which the yarn is adapted to draw, a pin having a bearing portion of enlarged diameter engaging 35 against the fixed blade to hold the pin with its side in parallel spaced relation with respect to the edge of the blade to form a slit for the yarn, and a resilient clamp for holding the pin with its bearing portion pressed against the blade.
4. In a device of the type specified, the combination of a stationary blade having an edge across which the yarn is adapted to draw, a pin having an enlarged bearing portion arranged eccentric to its axis and engaging against the 45 edge of the blade to hold the side of the pin in parallel spaced relation with respect thereto, and means for clamping the bearing portion of the pin against the edge of the blade to permit turning movement of the pin whereby its side may be adjusted toward and away from the edge of the blade to vary the width of the slit therebetween.
5. In a device of the type specified, the combination of a support, a blade fixed to said support and having an edge projecting laterally therefrom, a pin arranged with its side in opposite spaced relation with respect to the edge of the blade and having a bearing portion at one 55 end disposed eccentric to its axis, and a spring-clamp engaging over the bearing portion of the pin to hold it in fixed relation with respect to the blade while adapting it to be turned to adjust its side toward and away from the edge of the blade to vary the width of the slit therebetween.
6. In a device of the type specified, the combination of a support, a blade secured to said support overhanging its side, a pin having a cylindrical bearing arranged eccentric to its axis and adapted to engage the support and the edge 65 of the blade, and a spring-clamp having a portion partly encircling the bearing on the pin to hold the latter in place while adapting it to be turned to adjust its side toward and away from the edge of the blade.
7. In a device of the type specified, the com-

bination of a base having a channel extending laterally thereof formed with a seat in its bottom, a blade secured to the base with its edge overhanging the side of the channel, a pin extending parallel with the edge of the blade and having an enlarged bearing portion disposed eccentric to its axis resting on the seat in the channel and bearing against the edge of the blade, and a clamp engaging over the bearing portion of the pin to hold the latter on its seat abutting the edge of the blade while adapting it to be turned to adjust the side of the pin toward and away from the edge of the blade to vary the width of the slit therebetween.

8. In a device of the type specified, the combination of a base having a channel extending laterally thereof, a blade held on the base with its edge overhanging the side of the channel, a pin having an enlarged eccentric portion seated in the channel with its side abutting the edge of the blade, and a clamp-member secured to the top of the blade and having curved spring-fingers engaging across the top of the bearing portion of the pin to hold the latter seated in the channel with its side engaging the edge of the blade and its main portion projecting in opposite parallel spaced relation with respect thereto.

9. In a device of the type specified, the combination of a base, a blade fixedly secured to the base with its edge extending laterally therefrom, a pin having an enlarged eccentric portion bearing against the edge of the blade with its main portion extending in parallel spaced relation with respect to said edge, and a clamp-member provided with a plurality of spring-fingers engaging around the bearing portion of the pin, said bearing portion of the pin formed with a peripheral groove engaged by one of the spring-fingers on the clamp-member to hold the pin against longitudinal movement.

10. In a device of the type specified, the combination of a base, a blade secured to said base and having a yarn-scraping edge projecting laterally therefrom, a pin having a bearing portion formed with ratchet teeth adapted to engage the edge of the blade to hold the pin in parallel spaced relation with respect to the yarn-scraping edge of the blade, and resilient means for holding the bearing portion of the pin against the blade to adapt it to be turned to adjust the side of the pin laterally with respect to the edge of the blade.

11. In a device of the type specified, the combination of a base, a blade fixed to the base and provided with a yarn-scraping edge projecting laterally therefrom, a pin formed with a bearing portion having a series of teeth of different depth adapted to be successively engaged with the edge of the blade, and resilient means for holding the pin with its bearing portion engaging the edge of the blade while adapting it to be turned to adjust the side of the pin laterally with respect to the edge of the blade.

12. In a device of the type specified, the combination of a base having a channel extending laterally across its top, a blade secured to said base with its edge overhanging the side of the channel and projecting beyond the side of the base, a pin seated in the channel in the base and provided with an enlarged bearing portion having teeth of graduated depths adapted to engage with the lower edge of the blade, and a spring-member having a resilient curved portion overhanging the top of the bearing portion of the pin to hold the latter against its seat while adapting it to be turned to successively engage

the teeth with the edge of the blade whereby to adjust the side of the pin laterally with respect to the edge of the blade.

13. In a device of the type specified, the combination of a base having a channel extending laterally thereof, a blade secured to the base with its edge overhanging the side of the channel and extending outwardly from the side of the base, a pin having an enlarged bearing portion seated in the channel in the base and provided with peripheral teeth of graduated depth adapted to engage the edge of the blade, said bearing portion of the pin formed with a peripheral groove, and a resilient clamp-member secured to the top of the blade and having a curved portion overhanging the top of the bearing portion of the pin with a finger engaging the groove

therein to hold the pin from longitudinal movement and clamp it against the edge of the blade to adapt it to be turned to bring the successive teeth into engagement with the edge of the blade to adjust the side of the pin in lateral relation with respect to the edge of the blade.

14. In a slab-catcher or yarn-cleaner, the combination of a support, a blade mounted on said support with its edge in position to engage the yarn, a pin having a bearing portion of enlarged diameter engaging directly against the edge of the blade to position the side of the pin in spaced relation to said edge, and means for clamping the bearing portion of the pin against the edge of the blade.
